FEEDING AND STACKING MEANS FOR
ADDRESS PRINTING PLATES

Hermanus Hennink, Utrecht, Netherlands

Application June 25, 1947, Serial No. 756,948
In the Netherlands September 2, 1940Section 1, Public Law 690, August 8, 1946
Patent expires September 2, 1960

4 Claims. (Cl. 101—47)

1

This application is a continuation-in-part to my co-pending application Serial No. 629,736, filed November 20, 1945, now abandoned.

The invention relates to an addressing machine operating with plates and has for its object to simplify and to improve the device for conveying the used plates with which a print is made from the addressing machine to a tray or receiver collecting said plates in a stack.

A further object of the invention is to arrange the tray for the plates in such a way, that it may receive a great number of plates, e. g. a hundred or more, without increasing the normal height of the addressing machine and without the tray extending beyond the base of the addressing machine so that this machine does not need a specially constructed support but may be placed on any normal table.

Another object of the invention resides in a machine having a support for supporting a tray angularly and perpendicularly to the track for the plates, in which tray a follower is slidably arranged, a finger being provided to periodically shift the follower with the plates, if any, into such a position that each plate, when being ejected from the machine, falls upon the upper edge of the preceding plate in the tray and consequently tilts about an axis parallel to its longitudinal axis.

The drawing shows, by way of example, an embodiment of the addressing machine, whereby the arrangement of the tray and the manner in which the plates are edgewise stored in the tray are illustrated.

Figure 1 is a perspective view of the addressing machine,

Fig. 2 is a vertical longitudinal section,

Fig. 3 is a horizontal longitudinal section of the machine,

Fig. 4 is a side view of the machine, and

Fig. 5 is a schematic view showing the manner in which a plate enters the tray.

The addressing machine comprises a housing 1 resting on four rubber caps or feet 2.

Below the lid or cover 3 a track 5 is located for guiding the lowermost of the plates 6 which are piled between a guide 7 and a tray 8. This track 5 extends from the pile of plates 6 past the printing station, where the lid 3 is provided with an opening 4 to the ejecting end of the machine. The plates 6 descend by gravity and are moved toward the printing station 4 along the track 5 by a slide 9 to which reciprocating movement is imparted by a downward extension 10 of a printing arm 11, which is mounted to oscillate in a bearing 12.

2

At the end of the machine, where the plates are ejected from the track 5 a sloping support 13 is provided on which a tray 14 is placed into which the discharged plates are collected. This tray 14 which is maintained in place by a resilient member 15, Figure 1, which at the same time serves as a stop for the horizontal movement of the ejected plates 6. The tray is provided with a follower 16 slidably supported therein and against which the plates 6 will stack in the tray 14.

A finger 17 oscillating around an axle 18 is connected by arm 20 with the extension 10 of the printing arm 11 by means of a rod 19 and through the intermediary of an abutment member 21. This member 21 is biased by means of a tension spring 22 connected at one end 23 to a link 24 and the latter is secured to the abutment member 21 by an adjustable rod 25. The link 24 is pivotally connected by means of pin 26 to a short crank arm 27 connected through a collar 28 to a longer crank arm 29, the arms 27 and 29 and collar 28 being rotatably mounted on a shaft 30. As best seen in Figure 2, the arm 29 is connected to a depending arm 31 of the slide 9.

The device operates as follows: Each time the printing arm 11 is pushed downward for moving and reciprocating the feed slide 9 towards the right, Figure 2, from under the pile of plates 6, the finger 17 is moved to shift with its tip 31, Figure 3, the follower 16, together with any plates 6 already stacked in the tray 14, Figure 5, to the correct position for receiving the next plate 6, which is ejected from the track 5 upon the upward movement of the arm 11. This position is such that this next plate 6, after being completely freed from the track 5 and still in horizontal position, falls down and, touching the upper edge of the follower 16 or the foregoing or last plate 6 in the tray, tilts about a line parallel to its longitudinal axis and is thereby placed edgewise in the tray 14. Before a further plate 6 is ejected from the track 5 all plates and the follower 16 are again shifted to the proper position of the thickness of one plate by the finger 17.

What is claimed is:

1. In an addressing machine with a printing station in which the address plates pass horizontally and singly through the machine and into a receiving tray arranged under and at right angles to the horizontal path of travel of the individual plates through the machine, said tray being downwardly inclined relative to the path of travel of the used plates, a device for intermittently moving the used plates in the tray a distance approximately equal to the thickness of one plate and including a printing arm inter-

mittently operable and means structurally related to and responsive to the movement of the printing arm to move the plates in the tray and to feed a plate singly from the printing station to and over the receiving tray to strike the upper edge of the last stacked plate in the tray near one edge of the incoming plate, causing said incoming plate to tilt and fall substantially upright into the tray and adjacent the last stacked plate.

2. In an addressing machine having a plate feed and printing arm intermittently operable in which the address plates pass horizontally and singly through the machine and into a receiving tray arranged below and at right angles to the horizontal path of travel of the individual plates through the machine, said tray being downwardly inclined relative to the path of travel of the used plates, a pivoted finger operative to contact and move the stacked plates in the receiving tray a distance approximately equal to the thickness of one plate upon each operation of the printing arm, and means connected to the finger and to the plate feed and printing arm to intermittently move the stacked plates and the used plates so that each used plate will be moved over the receiving tray and to strike the last stacked plate near one edge so that such incoming plate will fall and turn at right angles to assume an upright position in the stack.

3. A method for returning address plates into a receiving tray which is located below and at approximately right angles to the path of travel of the plates through the machine and the receiving tray is downwardly inclined relative to the path of travel of the used plates in the same order in which they were placed in an addressing machine, comprising the steps of individually feeding the plates through the machine and delivering them singly to the receiving tray, simultaneously advancing the stacked used plates in the tray with each intermittently operable print-

ing stroke a distance approximately equal to the overall thickness of a plate and advancing each used plate over the stacked used plates so that one edge of each plate will contact the last stacked plate, so that the incoming plate will turn during its fall to align with and come to rest against the last stacked plate.

4. An addressing machine having printing plates and printing means, comprising a housing having a track for the printing plates, a support secured to the housing and arranged at right angles and inclined relative to the track for the plates, a tray on the support inclined downwardly with respect to the path of travel of the plates, a follower slidably arranged in the tray an oscillating finger pivotally mounted in the housing and operable to project over the tray for shifting the follower with the plates supported by it a distance equivalent to the thickness of one plate, means for intermittently actuating the printing means, and means responsive upon actuating the printing means for operating the finger and subsequently ejecting a plate into a position over the tray so that each plate when ejected from the machine falls upon the upper edge of the preceding plate in the tray and consequently tilts round an axis parallel to its longitudinal axis.
